Primary Examiner — T. Chase Nelson*Assistant Examiner* — Michelle E Wilson(74) *Attorney, Agent, or Firm* — Alston & Bird LLP(57) **CLAIM**

The ornamental design for a dishwasher rack, as shown and described.

DESCRIPTION

FIG. 1 is a perspective view of a dishwasher rack showing our new design;
 FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is another perspective view thereof, shown from the rear, left, and top.
 Broken lines are directed to unclaimed features and form no part of the claimed design.

1 Claim, 6 Drawing Sheets(56)
